UNITED STATES PATENT OFFICE

2,002,887

ROUTE FILE

Tom W. Flory, Ottawa, Kans.

Application July 6, 1934, Serial No. 734,038

6 Claims. (Cl. 45—58)

This invention relates to file holders, particularly those of the type intended to hold route cards employed by the drivers of delivery trucks and the like to record items of delivery and charge to customers along an established route.

An object of the invention is the provision of dash-board attachable route card file holding means arranged for convenient access when in service position upon the dash-board of a delivery vehicle.

Another object is the provision in a device of this character of dash-board carried means having a quick detachable supporting connection with route card file holding means.

Other objects will be apparent from the description.

While the present disclosure constitutes an illustrative embodiment of the invention, it is to be understood that the structural details thereof may be varied as desired within limit not inconsistent with the scope of the invention as claimed.

In the accompanying drawings:

Figure 1 is a top plan view of an assembled device constructed in accordance with the invention.

Figure 2 is a side elevation of the device as mounted in service position upon a vehicle dash-board, the dash-board being shown in section.

Figure 3 is an elevation of the dash-board carried support unit of the device.

Figure 4 is a group perspective illustrating the manner and means of establishing service connection between the separable elements of the device.

Figure 5 is an assembled perspective of the connector elements as in service position.

In detail, the device consists primarily of two parts one of which comprises a support 6, here shown as a rectangular block of wood or other suitable material arranged to be permanently attached to a dash-board 7 by suitable securing means, such securing means in this embodiment comprising bolts 8 seated transversely within the block and having threaded ends extending beyond the rear face thereof for engagement through suitably provided apertures, not shown, in the dash-board, and provided with clamping nuts 9 threaded over the bolt stems for clamping the support in the desired position on the dash-board.

The support 6 is provided with means for holding a small lamp 10, such as a dash lamp, a preferred embodiment of such holding means comprising a flat, upright, metal strap 11 suitably attached to the outer face of the support block and

extending a desired distance thereabove with its upper end 12 being quarter turned and formed to receive therein the socket assemblage 13 of the lamp, the lighting of which is controlled by the conventional switch 14. A flexible conduit 15 for the lamp wires extends between the lamp socket and the body of the support adjacent one end of the block. The lamp wires, not shown, are attached in the usual manner to the conventional lighting system of the vehicle.

Secured to the outer face of the support 6, midway between the ends thereof is a bracket, here shown as a metal strap 16 that extends at a downward angle an appreciable distance rearwardly of the support block and which is bent at its forward end to provide a downturned lip 17 attached to the block face by suitable securing elements, one of which is shown as at 18.

The support 6 is further provided with hangers 19 secured to its outer face adjacent each end. These hangers 19 are arranged to receive cooperating hook members 20 that are permanently attached to the second part of the device now to be described.

The second part of the device comprises a broad flat panel or board 21, carrying a pin file, here shown as of the arch type, having a base 22 suitably connected to the panel 21 with its upright arch pins 23 arranged to receive a plurality of loose leaf record blanks or cards 24 in the usual manner.

The hanger elements 19 each comprise a flat plate 25 adapted to be attached by securing elements 26 to the outer flat face of the support block 6. The plate 25 is cut out at its central portion resulting in webs 27 that are bent downwardly and outwardly with respect to the plate, terminating in reversely bent portions united to form a lip 28. The lip 28 functions as a keeper cooperating with an outwardly bent terminal lug 29, extending from a tongue 30 angled with respect to the plate 25 and anchored by inturned ears 31 that bear against the outer flat face of the support block. All parts of the hangers 19 are integral and, as shown in Figure 4, the lug 29 terminates in spaced relation from the keeper lip 28. The hook members 20 correspond in number to the hangers mounted on the support block, and these hook members in the present embodiment comprise flat plates 32 suitably secured to the under face of the panel 21 at its forward edge, each plate 32 having a downwardly offset lip 33 that extends forwardly of the forward edge of the panel 21. The offset lip portion 33 of each plate 32 is cut away to provide an upstruck tongue 34.

The support 6 is provided with means for holding a small lamp 10, such as a dash lamp, a preferred embodiment of such holding means comprising a flat, upright, metal strap 11 suitably attached to the outer face of the support block and

34 that terminates in a rearwardly extending forward tip 35, adapted to be driven into the forward edge of the panel 21 for a secure anchorage.

In service, the panel 21 with its mounted file 5 22 and record sheet 24 is detachably connected to its dash-board support element 6 by inserting the hook lip 33 between the hanger keepers 28 and the lug 29 and bringing the bottom of the panel to rest upon the rearwardly extending strap 10 16. In this operation the hanger tongues 29 engage in the apertured portions of the hook elements 20 to retain the lip 33 beneath the hanger lug, thus assuring positive connection between the hangers and hooks with the panel resting securely 15 in a convenient position upon the inclined supporting strap 16. At the end of a run or at any time that disengagement is desired, the panel 21 with its file holder may be disengaged as a unit from the supporting element 6 merely by tilting 20 the panel 21 upwardly to depress the lip 33, whereupon the hook elements may be drawn outwardly from between the keepers 28 and lugs 29. This structural assemblage provides a convenient route 25 for access and which may be removed without disturbing the arrangement of that portion of the device which remains permanently connected to the dash-board. The support element 6 is arranged at a convenient location on the dash-board and the dimensions are such that no portion 30 of the device extends above the upper edge of the dash to interfere with vision through the windshield.

35 I claim:

1. A dash-board file holder comprising a dash-board attached support, a lateral bracket arm carried thereby and extending rearwardly therefrom, a file holder panel adapted to be seated on 40 said bracket, and cooperatively engageable connector means carried respectively by the forward edge of the panel and said support on either side of said bracket arm.

2. A dash-board file holder comprising a dash-board carried support, a file holder panel de- 45

tachably hinged to said support at spaced points, and a holding bracket on said support for engaging the bottom of said file holder panel between the hinge connections.

3. A dash-board file holder comprising a supporting block, means for attaching said block to a dash-board, spaced hangers carried by said block, a file holder panel, spaced hook members carried by said panel for detachable engagement with said hangers, and an inclined bracket arm 10 extending rearwardly from said support block between said hook members and hangers for engagement with the bottom of said panel.

4. A dash-board file holder comprising a dash-board carried block provided with spaced hangers, each having keeper means, a bracket extending laterally from said block between said hangers, a file mounting panel adapted to rest on said bracket, and hooks on said panel adapted for detachable engagement with said keeper means.

5. In a dash-board file holder, a support arranged for permanent connection to a dash-board, a bracket extending laterally from one face of said support, a file holder panel adapted to seat 25 on said bracket, detachable connector means on said panel and support on each side of said bracket, and a light holder attached to said support adjacent the bracket on the same face therewith and extending above the support and bracket be- 30 tween said connector means.

6. In a dash-board file holder, a support block arranged for permanent connection to a dash-board, a single flat bracket arm extending laterally rearward from the rear face of said block 35 below its upper edge and inclining rearwardly, a connector on said rear face of the block at each side of said bracket arm below the upper edge of the block, a flat file holder panel seated on said arm and detachable connectors on said panel extending beyond its front edge for engagement with said support block carried connectors to retain said panel on said bracket arm.

TOM W. FLORY.
